DESIGN FOR A TRANSPARENT CIGAR CONTAINER

August Baer, New York, N. Y.

Application April 25, 1940, Serial No. 91,937

Term of patent 7 years

To all whom it may concern:

Be it known that I, August Baer, a citizen of the United States and a resident of the city of New York, in the county of New York and State of New York, have invented a new, original, and ornamental Design for a Transparent Cigar Container, of which the following is a specification, reference being had to the accompanying drawing forming a part thereof.

The figure is a perspective view of the transparent cigar container showing my new design.

The design is characterized by a transparent container of the contour shown, having a top cover member disposed in the manner shown with a centrally superposed member as shown extending from the said top cover member of said container.

I claim:

The ornamental design for a transparent cigar container, substantially as shown and described.

AUGUST BAER.
